UNITED STATES PATENT OFFICE.

JAMES E. GREENAN, OF ASHTON, RHODE ISLAND.

VOTIVE STAND.

Application filed August 26, 1926. Serial No. 131,650.

My invention relates to votive or vigil light stands. The objects of my invention are broadly to beautify the appearance of present day votive stands and to substantially eliminate the fire hazard.

So far as I am aware the former types of votive stands have been provided with an open drip pan underneath the burning candles into which the wax from the candles 10 drips. This mass of wax has provided a very unsightly appearance and as it has often caught fire, has caused continuous fire hazards in churches where votive stands have been employed.

15 I completely eliminate the open frame work of former types of votive stands and completely enclose the drip pan within an air tight, non-inflammable container. The outer exposed surface of the container may 20 be ornamented thereby beautifying its appearance. Holes are bored through the top of the container adapted to receive the candles or vigil light holders and the waste therefrom drips into the concealed drip pan below. It is obvious that as I have 25 completely concealed the drip pan within a substantially air tight container thereby cutting off the supply of oxygen, that I have practically eliminated the possibility of combustion therein.

30 To further lessen the fire hazard I have provided a fence surrounding the top of the container adapted to catch any candles that might fall. This fence may be beautified in 35 any desired manner. I preferably arrange the top of the container in the form of stairs, similar to those of an altar, thereby providing the votive stand with a more beautiful and symmetrical appearance than hitherto, 40 and to permit the lowest stair tread to act as a trough to catch candles falling forward.

If desired, a coin box having a slot accessible from without the container may be concealed within the container, and also if desired a receptacle for candles may also be suitably concealed within the container, said coin box and candle receptacle in my preferred embodiment being located underneath the lowest stair tread, which is normally not provided with holes for candle holders.

These and such other objects of my invention as may hereinafter appear will be best

understood from a description of the accompanying drawings, which illustrate an embodiment of my invention. 55

Fig. 1 is a perspective view of my improved votive stand suitably mounted on a table.

Fig. 2 is a cross sectional view thereof 60 taken through the centre of the container.

Fig. 3 is a vertical sectional view taken along the line 3—3 of Fig. 2.

Fig. 4 is a rear elevation of my improved container showing the air tight door in 65 raised position for the removal of the drip pan.

In the drawings, wherein like characters of reference indicate like parts throughout, 10 generally indicates a suitable enclosed, 70 substantially air tight preferably rectangular container, which completely encloses the drip pan 12. The base of said container 10 normally rests on the top of a table 16 or on any other suitable base. The top 18 of the container is provided with the holes 20 cut there-through at desired spaced intervals thereon. To provide a vigil light stand of a more 75 beautiful appearance than hitherto and which may be suitably ornamented in accordance 80 with any desired type of church architecture or other design, I preferably construct the top 18 of said container in the form of stairs 22. The lowest stair tread 24 is not provided with the holes 20, but preferably 85 forms a trough to catch falling candles 28 normally contained as usual within the holes 20. I preferably provide a fence 30 extending upwards around the entire top 18 of the container to prevent candles from falling 90 outside of the container. Whereas my container may be constructed in any suitable manner, I preferably construct it as follows:

The portion of the fence 30, adjacent to the front 32, the back 34 and sides 36, is normally constructed as shown integral therewith, each preferably from a single sheet or casting. The front 32 and back 34 are suitably secured to the sides 36 by having co-operating threaded projections 42 cast integral 100 therewith, adapted to receive the screws 44 to hold said individual castings or sheets together, and said members are also provided with the integral threaded projections 46 adapted to receive the screws 44 to attach 105 them to the base 40.

I normally provide the partition 50 to divide the space underneath the lowest stair tread into a front compartment 52 apart from the back compartment 54 located underneath the upper stairs 22. I therefore 5 preferably construct the top 18 of my improved container of at least two parts, namely, the part 58 formed in the shape of the upper stairs 22, the lowest stair tread there- 10 of being provided with the depending riser or partition 50 extending to the bottom 40 of the container and spaced from the front 32 thereof, and lowest stair tread 24. The front 32, back 34, and sides 36 are normally 15 provided with the treaded projections 59 adapted to receive the screws 44 suitably threaded through the top 18 to secure the top 18 thereto. The space underneath the front stair tread 24 as more particularly 20 shown in Fig. 3, normally contains the coin box 60 suitably provided with the cover 62 and the lock 64, the top cover 62 thereof forming a portion of the lowest stair tread 24. Said coin box 60 is preferably provided 25 with the coin slot 66 normally accessible from the outside of the container. The balance of the front compartment 52 underneath the lowest stair tread 24 may normally 30 form a candle receptacle 70 adapted to receive the candles 72 therein. In my preferred embodiment I have shown two candle receptacles 70, one on each side of the centrally located coin box 60. If desired, the coin box 60 may be omitted and the entire 35 space underneath the lowest stair tread 24 or the entire front compartment 52 may be a candle receptacle. In my preferred embodiment I have provided a removable cover 74 for each compartment 70. Though said 40 cover may be attached in any suitable manner, such as by hinges if desired, in my preferred embodiment I preferably form the lugs 76 integral with the lowest stair riser 50 and the rear side of the front 32, on 45 which said cover 74 is adapted to rest and I provide said cover 74 with the handles 77 adapted to be grasped by the hands to remove the cover 74 from the container 70. It is obvious that the removable cover 74 50 for the candle container 70 and the cover 62 of the coin box form the entire front stair tread 24, covering the front compartment 52.

As stated, the entire portion underneath the upper stair treads 22 comprises the back 55 compartment 54 of my invention. I preferably provide the air tight door 80 to said compartment 54, in my preferred embodiment preferably located in the back thereof. In my preferred embodiment I construct 60 said door 80 so that it may slide upwards and provide it with the lifting handles 82. The door 80 is normally retained against the upper portion of the back 36 when in raised position, by the spaced lips 84, which form 65 the channels 86 for the door 80 to slide up

and down thereon. It is obvious that in place of the construction shown, the door 80 may be suitably pivoted or otherwise attached to any desired part of the container 10.

In addition, as explained, I provide the drip pan 12 completely enclosed within the container 10 underneath the vigil light or candle receiving holes 20 in the upper stair treads 22. Said drip pan 12 is shown as a 70 split tray 12 but it is obvious that it may take the form of a pan, or any other desired configuration. Said drip pan may be readily removed if desired through the opened air tight door 80.

It is obvious that by completely enclosing the drip pan within the container and providing a votive stand in the form of an enclosed container, I have clearly beautified 80 votive stands. By constructing said container in the form of a stairs, I have further beautified the configuration thereof. It is obvious that I have clearly improved the appearance of votive stands by completely enclosing from view the drip pan. It is 90 obvious that I have provided a configuration which may be readily ornamented if desired.

It is also obvious that I have substantially eliminated the fire hazard by practically 95 completely cutting off the supply of oxygen from the drip pan, by enclosing the top of the votive stand with a suitable fence to catch falling candles, and by providing a suitable trough to catch falling candles.

Though I have shown the container constructed of sheet or cast metal, it is obvious 100 that it may be constructed of any suitable material in a manner to make it relatively noninflammable.

It is understood that my invention is not 105 limited to the specific embodiments shown and that various deviations may be made therefrom without departing from the spirit, basic principles and scope of the appended claims.

What I claim as new and desire to secure by Letters Patent is:

1. A votive stand or candelabrum comprising, in combination, a substantially air tight container having a plurality of spaced holes through the top thereof to receive the candles or vigil light holders, a fence around the top to catch falling candles and an air tight door, a drip pan normally contained within the said container underneath said holes and removable through said air tight door, a coin box concealed within the container having a coin slot accessible from without the container, and a candle receptacle concealed within said container accessible other than through said drip pan door.

2. A votive stand or candelabrum comprising, in combination, a substantially air tight container having a plurality of spaced holes through the top thereof to receive the

- candles or vigil light holders and a drip pan normally contained within the said container underneath said holes.
3. A votive stand or candelabrum comprising, in combination, a substantially air tight container having a plurality of spaced holes through the top thereof to receive the candles or vigil light holders, a drip pan normally contained within said container underneath said holes, and a fence around the top to catch falling candles.
4. A votive stand or candelabrum, comprising, in combination, a substantially air tight container having a plurality of spaced holes through the top thereof to receive the candles or vigil light holders, a drip pan normally contained within said container underneath said holes, and a coin box concealed within the container having a coin slot accessible from without the container.
5. A votive stand or candelabrum comprising, in combination, a substantially air tight container having a plurality of spaced holes through the top thereof to receive the candles or vigil light holders, a removable drip pan normally contained within the said container underneath said holes, and a candle receptacle concealed within said container.
6. A votive stand or candelabrum comprising, in combination, a substantially air tight container having a plurality of spaced holes through the top thereof to receive the candles or vigil light holders, and an air tight door, and a drip pan normally contained within the said container underneath said holes, removable through said air tight door.
7. A votive stand or candelabrum comprising, in combination, a substantially air tight container having the top thereof shaped in the form of stairs, the upper stair treads having a plurality of spaced holes therethrough to receive the candles or vigil light holders and the lowest stair tread forming a trough to catch falling candles, a fence around the top to catch falling candles, a partition dividing the space underneath the lowest stair tread into a front compartment apart from the back compartment underneath the upper stair treads, and a drip pan normally contained within the back compartment underneath said holes.
- 40 8. A votive stand or candelabrum comprising, in combination, an enclosed container having the top thereof shaped in the form of stairs, the upper stair treads having a plurality of spaced holes therethrough to receive the candles or vigil light holders, and the lowest stair tread forming a trough to catch falling candles and a lockable coin box located within the front portion of the container under the lowest stair tread, having a coin slot accessible from the outside of the container, the top thereof forming a part of the lowest stair tread, and a drip pan normally contained within said container underneath said holes.
- 45 9. A votive stand or candelabrum comprising, in combination, an enclosed container having the top thereof shaped in the form of stairs, the upper stair treads having a plurality of spaced holes therethrough to receive the candles or vigil light holders and the lowest stair tread forming a trough to catch falling candles and a fence around the top to catch falling candles, and a drip pan normally contained within said container underneath said holes.
- 50 10. A votive stand or candelabrum comprising, in combination, a substantially air tight container having the top thereof shaped in the form of stairs, the upper stair treads having a plurality of spaced holes therethrough to receive the candles or vigil light holders and the lowest stair tread forming a trough to catch falling candles and a partition dividing the space under the lowest stair tread into a front compartment apart from the back compartment underneath the upper stair treads, and a drip pan normally contained within the back compartment underneath said holes.
- 55 11. A votive stand or candelabrum comprising, in combination, an enclosed container having the top thereof shaped in the form of stairs, the upper stair treads having a plurality of spaced holes therethrough to receive the candles or vigil light holders and the lowest stair tread forming a trough to catch falling candles and a lockable coin box located within the front portion of the container under the lowest stair tread, having a coin slot accessible from the outside of the container, the top thereof forming a part of the lowest stair tread, and a drip pan normally contained within said container underneath said holes.
- 60 12. A votive stand or candelabrum comprising, in combination, an enclosed container having the top thereof shaped in the form of stairs, the upper stair treads having a plurality of spaced holes therethrough to receive the candles or vigil light holders and the lowest stair tread forming a trough to catch falling candles, a candle or vigil light receptacle underneath the lowest stair tread, provided with a removable cover, and a drip pan normally contained within said container underneath said holes.
- 65 13. A votive stand or candelabrum comprising, in combination, a substantially air tight container having the top thereof shaped in the form of stairs, the upper stair tread having a plurality of spaced holes there-

through to receive the candles or vigil light holders and the lowest stair tread forming a trough to catch falling candles and having an air tight door, and a drip pan normally contained within said container underneath said holes, and removable through said air tight door.

14. A votive stand or candelabrum comprising, in combination, an enclosed container having the top thereof shaped in the form of stairs, the upper stair treads having a plurality of spaced holes therethrough to receive the candles or vigil light holders and the bottom stair tread forming a trough to catch falling candles, a partition dividing

the space underneath the lower stair tread into a front compartment apart from the back compartment under the upper stair treads, the front compartment forming a candle or vigil light receptacle provided with 20 a removable cover forming the front stair tread, an air tight door to the back compartment and a drip pan normally contained within the back compartment underneath said holes and removable through said air 25 tight door.

In testimony whereof I affix my signature.

JAMES E. GREENAN.
